HIS ATTORNEY'S

UNITED STATES PATENT OFFICE.

EDWIN L. WHITE, OF BROOKLYN, NEW YORK, ASSIGNOR TO J. H. WHITE MANUFACTURING CO., OF BROOKLYN, NEW YORK, A CORPORATION OF NEW YORK.

DESIGN FOR A CANOPY.

44,551.

Specification for Design.

Patented Aug. 19, 1913.

Application filed May 29, 1913. Serial No. 770,803. Term of patent 7 years.

To all whom it may concern:

Be it known that I, EDWIN L. WHITE, a citizen of the United States, residing at the borough of Brooklyn, in the county of Kings and State of New York, have invented a new, original, and ornamental Design for a Canopy, of which the following is a specification, reference being had to the accompanying drawing, forming part thereof.

Figure 1 is a plan view of a canopy, showing my new design, and Fig. 2 is a side elevation of the same.

I claim:

The ornamental design for a canopy, as shown.

EDWIN L. WHITE.

Witnesses:

A. H. MOWEN,
CHAS. SCHAFERMAN.
